UNITED STATES PATENT OFFICE

102,956

DESIGN FOR A BODY FOR TWO-WHEELED VEHICLES

Charles Stanley Prince, Washington, D. C.

Application December 8, 1936, Serial No. 66,391

Term of patent 7 years

To all whom it may concern:

Be it known that I, Charles Stanley Prince, a citizen of the United States, residing at Washington, in the District of Columbia, have invented a new, original, and ornamental Design for Bodies for Two-Wheeled Vehicles, of which the following is a specification, reference being had to the accompanying drawings, forming part thereof.

Fig. 1 is a side elevation of a body for two wheeled vehicles showing my new design;

Fig. 2 is a top view thereof;
Fig. 3 is a bottom or inverted plan view thereof;
Fig. 4 is a front end elevation of the same; and
Fig. 5 is a front perspective view thereof.

I claim:

The ornamental design for a body for two-wheeled vehicles, substantially as shown.

CHARLES STANLEY PRINCE.
